UNITED STATES PATENT OFFICE

2,526,260

APPARATUS FOR ILLUSTRATING RELATION
BETWEEN ECONOMIC PROFIT AND LOSS

James D. Mooney, Oyster Bay, N. Y.

Application October 8, 1948, Serial No. 53,562

3 Claims. (Cl. 35—24)

1

This invention relates to illustrating business economics by physical analogies and using such analogies as an aid to the solution of business problems.

Circular charts divided into segments of varying size have long been used to illustrate the division of income into various types of expenses and the balance remaining, i. e., profits. Column charts have also been employed. Such charts, however, show the relationship between a fixed set of conditions. In actual practice conditions never are fixed and variations in conditions produce most important results. For example, it is well known that while some cost items are directly proportional to sale or output volume, others are not. As a result, when a factory is working at only one-third its full capacity, it may lose money, whereas, with no increase in the sale price of its product, it would make a handsome profit if it were operating at or near capacity.

Attempts have been made to chart this variable relation between the volume of output or sale of goods and profits. This is only a partial solution of the problem since the chart assumes all factors other than the volume of output or sale of goods are fixed. Consequently, to show the result of varying these other factors additional charts are needed.

The chief object, therefore, of the present invention is to provide simple means for demonstrating quantitatively, as well as qualitatively, the effect of changing any one or more of a whole series of factors on the final desired result of the operation of any business, viz: how much cash is available, after all expenses have been paid, for distribution to its owner or owners.

This is accomplished, broadly speaking, by dividing a predetermined volume of liquid, corresponding to some selected figure for factory output or sales, into a series of likewise predetermined smaller volumes representing various classes of expenditures. It is a matter of dividing income into a series of outgoes and noting what is left over.

In my prior United States Patent No. 2,297,011, issued September 29, 1942, apparatus of this general type was illustrated. While in many respects the apparatus shown in that patent is similar to the present one, in other ways it has been very materially modified, simplified, and improved.

In demonstration apparatus of the present type the fewer distractions the better. Where much of the working mechanism is exposed to view, there is a strong tendency to watch the wheels go round instead of observing the effects simulating the economic changes and laws to be demonstrated.

One of the principal objects of the present invention is to improve the construction shown in

my prior patent by reducing the number of operating parts visible to the eye and hence reduce distracting features to a minimum.

In the previous form of construction the liquid above each piston was returned to the sump by letting it run into the bottom of the cylinder and then drain out from there. Not only was the discharge flow of liquid visible, but also the valve operating mechanism which permitted such discharge could be seen.

A further object of the present invention, therefore, is to provide means for discharging the liquid above the piston through the piston rod instead of into that part of the cylinder below the piston, thereby concealing the discharge flow of liquid.

As the piston rods are arranged so that their position can be adjusted vertically, it follows that the point of discharge of liquid therefrom varies likewise. With the piston rod near its top position, there is necessarily considerable distance between the bottom of the rod and the liquid level in the sump into which the liquid discharges so that, unless means are taken to prevent it, considerable splashing will occur.

A fixed sleeve surrounding the lower part of the piston rod cannot be used as it would interfere with the valve operating mechanism at the lower end of the rod. According to this invention, therefore, splashing of the liquid leaving the piston rods is avoided by attaching flexible canvas or similar tubes to the bottom of each piston rod. These flexible tubes collapse as the rods are lowered so that their discharge ends are always near or below the level of the water in the sump.

Discharge into the lower part of the cylinder also necessitates either making the lower part of each cylinder liquid tight, with several resulting disadvantages, or allowing liquid to slop over the machine, an undesirable method.

For demonstration purposes the main parts of the apparatus should not be more than chest high. This restricts the vertical space for the working parts. With limited available height, the piston rods cannot be made much longer than the cylinders and hence parts at least of such rods entering the cylinders have to be provided with threads or rack teeth by which they can be moved vertically. The presence of these threads or rack teeth prevents the use of glands to ensure a tight joint. This necessitates an upstanding collar or sleeve surrounding the piston to prevent liquid passing out around the piston rod. A similar difficulty was experienced with the earlier construction in connection with the square section rotatable valve-opening rod which passed through the bottom of the cylinder.

Another disadvantage of the earlier apparatus was that the valve in the piston was raised and

lowered by turning a vertical rod about its axis. This required complex mechanism for converting angular motion about a vertical axis into linear vertical to and fro motion.

According to the present invention, the valve is mounted on top of a rod inside the hollow bore of the piston rod. The lower end of this rod is attached to a crank on a horizontal shaft mounted in the bottom of the piston rod.

With this new construction it is necessary to connect the various shafts at the bottoms of the piston rods with a control shaft in such a way that the piston rods can be raised or lowered without change in the relative angular position of the two shafts. While this may be accomplished by bevel gears on both the main shaft and each individual shaft operatively connected by bevel gears at the ends of a corresponding series of telescopic cross-shafts, a simpler method is to use sprocket and chain connections which permit the same relative movements.

A further object is to provide a construction by which the height of the pistons in each cylinder can be rapidly and easily adjusted by hand, thereby avoiding the expense and complication resulting from the use of electric motors for such purpose.

In the earlier construction, the piston rods were threaded and were raised and lowered by turning nuts on the rods. This involves many turns of the nuts to move the piston rods from topmost to lowermost position. Consequently, electric motors were used to turn the nuts.

According to the present invention, the piston rods are raised and lowered by racks and pinions. Two or three turns of the pinions is all that is required and that can be done by hand more simply and quicker than by the old motor-driven nuts.

A prior art form of fixed chart and also a suitable embodiment of the present invention are shown, by way of example, in the accompanying drawings, in which:

Fig. 1 shows one of the prior art economic "cross-over" or break-even point charts;

Fig. 2 is a perspective view of the apparatus as a whole;

Fig. 3 is a front elevation, partly in section, of those parts of the apparatus which are vital from the demonstration viewpoint;

Fig. 4 is a detail elevation partly in section of two adjacent cylinders;

Fig. 5 is a vertical central section through one of the pistons, its piston rod, valve and associated operating parts;

Fig. 6 is a section on the line 6—6 of Fig. 5;

Fig. 7 is a section on the line 7—7 of Fig. 5;

Fig. 8 is a section on the line 8—8 of Fig. 5;

Fig. 9 is a perspective diagrammatic view of the main valve-control shaft, piston-rod shafts, intermediate jack-shafts, and the connecting chains and sprockets;

Fig. 10 is an end elevation of one of the valve control chain and link set-ups;

Fig. 11 is a section on the line 11—11 of Fig. 10;

Fig. 12 is a detail end view with parts broken away of the piston rod raising and lowering mechanism; and

Fig. 13 is a section on the line 13—13 of Fig. 12.

The chart shown in Fig. 1 is given to illustrate the prior art type of chart with one variable only. One ordinate 1 is a scale of "Values." The other ordinate 2 is a scale of "Costs" and "Profit." The abscissa 3 is a scale of "Sales capacity."

Sales capacity is the only variable, so the chart is capable of showing the "Economic cross-over range" for a fixed sale price for the goods and fixed costs only. While some of the costs, such as labor and material, vary with the sales output, the basis for computing them is fixed. If wages go up 15% and material costs rise 9%, the chart is useless. It will be evident that the "Economic cross-over range" will occur at a higher sales output, but at what value of output cannot be told from the chart. Another chart would have to be drawn to take into account the new wage rates and material cost figures.

The apparatus of Figs. 2 to 13 comprises a cabinet 10 on casters 11 which serves the double purpose of supporting the tanks and cylinders required for demonstrating the economic laws hydraulically and of concealing the working parts from view.

On a shelf 12 near the top of the cabinet is a "Cash income" tank 15 arranged to be supplied with a predetermined amount of a suitable liquid such as colored water, by a pipe 16 including valve 17 and sump 18 driven by a motor 19 from a sump tank 20.

A T-connection 22, in the pipe 16, couples the latter to a pipe 23 leading to the sump to enable liquid in tank 15 to be drained off partially or wholly. A valve 24 opens and closes this pipe 23.

At a lower level than the tank 15 are a series of cylinders 25 to 32. A pipe 34 equipped with a valve 35 is provided for discharging the fluid from the tank 15 into the first cylinder 25. Each of these cylinders except the last, 32, has an overflow spout 36 arranged so that when it is full the excess liquid will overflow into the next cylinder in the line. These cylinders are labelled "Fixed charges," "Direct labor," "Indirect labor," "Direct materials," "Other factory expenses," "General and administrative," "Sales expenses" and "Gross profits."

The division of income from sales into the various expense items and ultimate gross profit will vary with the nature of the product manufactured and sold. For some products labor costs will be the main item. For others it will be materials. Similar variations will occur in connection with the minor expense items. Consequently, means are provided for changing the volume of each cylinder available for the receipt of liquid to control the proportion of liquid received by each cylinder to correspond with the proportion of "Cash income" which must be credited to "Fixed charges," "Direct labor," etc. One convenient way of changing the effective volume of the cylinders is to provide each cylinder except the last one with a vertically adjustable piston 37.

To enable specific situations to be demonstrated, scales representing dollars of cash income and expenditures are provided. Alongside the tank 15 is a numbered scale 39 and a series of numbered scales 40 are provided at the side of each cylinder. The scale beside the "Cash income" tank reads from the bottom upwardly because it is drained to fill the expenditure and profit cylinders. The scales beside the cylinders, except the last one, read from the top down, since the amount of liquid they contain varies from the top down to the top of the pistons in the various cylinders.

The construction of the pistons and the mechanism for raising and lowering them is shown in detail in Figs. 5, 6, 11, 12 and 13. Each piston

37 comprises two disks 41 and 42, the lower one resting on a shoulder on the hollow piston rod 43. The upper disk 42 has threaded engagement with the upper end of the rod 43. Clamped between these disks is a cup leather 44.

Secured to one side of each piston rod is a rack 46 with which meshes a pinion 47 on a shaft 48. Non-rotatably mounted on the same shaft is a worm wheel 49, turned by a worm 50 on shaft 51. A hand wheel 52 allows the worm to be rotated manually. The piston rod and rack is held against the pinion 47 by a guide wheel 54 and steadied laterally by guide wheels 55.

At the end of each operation of the apparatus, each cylinder has to be emptied and the liquid returned to the sump 20. This is done by raising a valve 56 off its seat on the top of the hollow piston rod, thereby permitting the liquid to flow down through the piston rod. For raising and lowering the valve 56, the latter is mounted on the top of a rod 57, the lower end of which is connected to a shaft 58 by a crank 59. When the crank is in its lowermost position, as shown in Fig. 5, the valve is closed. As shown in Fig. 8, the valve 56 has threaded engagement with the top of the rod 57 so that the vertical position of valve can be accurately adjusted. A lock-nut 61 holds the valve in adjusted position.

The shaft 58 is journaled in a fitting 60 secured by a set-screw 61 (Fig. 5) to the bottom of the piston rod. Means are provided for turning all of the shafts 58 and their cranks 59 simultaneously through the same angle irrespective of the vertical positions of the piston rods. This requires that the piston rods can rise and fall without changing the angular position of the cranks.

The mechanism for turning the shafts 58 and their cranks 59 is shown diagrammatically in Fig. 9. There is a single main control shaft 61 adjacent the lower part of the apparatus. It is turned manually, when desired, by a handle 62 at a convenient height above the ground connected to shaft 61 by sprocket 63, chain 64, sprocket 65, and shaft 66.

Parallel to the shaft 61 are a series of jack shafts 70, each of which is pivotally connected to the shaft 61 by a pair of interconnected links 71. Each shaft 70 is also pivotally connected to the shaft 58 of the adjacent piston rod by a pair of interconnected links 72. Shaft 61 is rotatably connected to shaft 70 by sprocket 73, chain 74, and sprocket 75. In turn, shaft 70 is rotatably connected to shaft 58 by sprocket 76, chain 77, and sprocket 78.

The pairs of links 71 and 72 permit the shafts 58 to rise and fall with the piston rods without changing the spacing between the shafts 61 and 70, on the one hand, and the shafts 70 and 58 on the other. The sprocket-chain connections between the three shafts allows the shafts 58 to rise and fall without changing their angular position.

To prevent liquid discharged through the hollow piston rods splashing when it strikes the liquid in the sump 20, thin-walled flexible canvas or similar tubes 80 are attached to the bottom of each piston rod, as shown in Fig. 5. These flexible tubes are long enough to reach the bottom part of the sump 20 when the piston rods to which they are attached are in their uppermost positions. As the rods are moved downwardly the lower ends of these flexible tubes strike the bottom of the sump and are pushed sideways.

I claim:

1. A device for illustrating the distribution of

income between a series of classified expenditures, comprising a row of vertical transparent cylinders each open at the top for receiving liquid to represent money expended, an overflow spout at one side of each cylinder, a piston and piston rod in each cylinder, the piston rods extending downwardly from the pistons and being hollow to allow discharge of liquid above the pistons when desired, valves for closing the bore in said rods at their upper end, means for opening and closing said valves operable independently of the vertical position of said pistons and piston rods, a shallow sump extending the length of said row of cylinders below the lower ends of the piston rods to receive liquid discharged from the cylinders through said rods, and a collapsible extension from the lower end of each of said rods into said sump to prevent splashing of liquid during such discharge.

2. A device for illustrating the distribution of income between a series of classified expenditures, comprising a row of vertical transparent cylinders each open at the top for receiving liquid to represent money expended, an overflow spout at one side of each cylinder, a piston in each cylinder, hollow piston rods extending downwardly from the pistons, valves for closing the bores in said rods at their upper end, means for opening and closing said valves, a horizontal valve-control shaft parallel to the row of cylinders, a horizontal shaft parallel to the valve-control shaft rotatably mounted on the lower part of each piston rod for operating said valve opening and closing means, and operative connections between the valve-control shaft and each of the shafts mounted on the piston rods constructed so as to allow the shaft on each piston rod to move vertically as a whole with such rod without change in the relative angular position of the shafts.

3. A device as claimed in claim 2 in which each of the operative connections between the valve-control shaft and each of the shafts on the piston rods comprises a pair of sprockets, one non-rotatably mounted on the valve-control shaft and the other non-rotatably mounted on the piston-rod shaft, another pair of sprockets non-rotatably mounted on a jack shaft, links, one connecting said valve-control shaft to the jack shaft and another connecting the jack shaft to the piston-rod shaft to maintain the spacing between said shafts constant while permitting the rotation of said shafts, and a pair of chains one operatively connecting the sprocket on the valve-control shaft to one of the sprockets on the jack shaft and the other operatively connecting the other sprocket on the jack shaft with the sprocket on the piston-rod shaft.
